D. J. SULLIVAN & C. F. STEVENS.
DEVICE FOR DRAWING PARALLEL LINES.
APPLICATION FILED JUNE 3, 1916.

1,227,854.

Patented May 29, 1917.

UNITED STATES PATENT OFFICE.

DANIEL J. SULLIVAN AND CARLETON F. STEVENS, OF CARSON CITY, NEVADA.

DEVICE FOR DRAWING PARALLEL LINES.

1,227,854.

Specification of Letters Patent. Patented May 29, 1917.

Application filed June 3, 1916. Serial No. 101,583.

To all whom it may concern:

Be it known that we, DANIEL J. SULLIVAN and CARLETON F. STEVENS, citizens of the United States, residing at Carson City, 5 in the county of Ormsby and State of Nevada, have invented certain new and useful Improvements in Devices for Drawing Parallel Lines, of which the following is a specification.

This invention relates in general to a device for drawing parallel lines, and particularly, to a straight edge which is so constructed as to enable it to be readily applied to a conventional type of ruler and 10 coöperate therewith for facilitating the drawing of evenly spaced and accurate parallel lines.

The primary object of the invention is to provide an attachment for rulers of a very 20 cheap and simple construction, and particularly, one which may be easily applied to a ruler, and which, when applied, will enable evenly spaced parallel lines to be readily drawn.

A further object of the invention is to construct the device in a manner to enable the ruler to which the device is applied, to 25 be used as originally intended.

The invention will be more readily 30 understood upon reference to the accompanying drawing, in which—

Figure 1 is a view illustrating the use of the invention:

Fig. 2 is an end view of the device as 35 unfolded;

Fig. 3 is an end view of the device folded;

Fig. 4 is an enlarged view of the straight 40 edge unfolded showing the ruler in dotted lines secured thereto;

Fig. 5 is a sectional view on the line 6—6, Fig. 4.

Referring to the drawings in detail, 1 represents a conventional type of ruler which 45 is provided with a graduated scale along one of its edges. 2 represents the straight edge which comprises a pair of foldable sections 3 and 4, one of which, namely, section 4, having a tongue 5 which extends from 50 the section in a direction longitudinally of the ruler to which it is applied. This tongue 5 serves as means for securing the straight edge to the ruler, and in order that it may be secured thereon, it is provided 55 with openings 6 for receiving suitable screws which are fastened into the body of

the ruler. In order that the straight edge will be rigidly fastened to the ruler to prevent any inaccuracy in the device, caused by accidental displacement of the straight edge, 60 the tongue 5 is provided with a prong 7 which is struck up from its surface and adapted to be embedded in the body of the ruler. As stated, the straight edge comprises a pair of foldable sections 3 and 4. 65 The section 3 is preferably provided with a graduated scale along one of its edges, preferably its inner edge, corresponding to the scale of the ruler. This section 3 is secured to the fixed section 4 by the hinged 70 connection 8 which renders it readily foldable. When the device is to be used for drawing evenly spaced parallel lines, the section 3 of the straight edge will project, as shown in Figs. 4 and 1, at a right angle 75 to the ruler, and when the ruler is to be used as originally intended, the section 3 may be folded upon the fixed section 4, and as the length of the section 3 is equal to the width 80 of the ruler and also the fixed section 4, the straight edge of the ruler will not be interfered with.

While the straight edge is preferably intended for use in connection with a wooden ruler, it may be also used in connection with 85 a ruler, composed of any other desirable material.

A device produced, as above described, is very cheap in construction and readily applied to a ruler. These features would enable the straight edge to be manufactured 90 and sold on the market either separately from the ruler, or as applied to a ruler.

We claim:

1. In combination with a ruler, a straight 95 edge coöperating therewith for drawing parallel lines, said straight edge comprising a pair of hinged sections, one of which is fixed to the ruler in a manner to permit the other section to project at a right angle 100 from the ruler, said projecting section provided with graduations along one of its edges and having a length equal to the width of the ruler and adapted to be folded upon the fixed section to permit of the ruler being used as originally intended.

2. In combination with a ruler, a straight 105 edge coöperating therewith for drawing parallel lines, said straight edge comprising a pair of hinged sections, one of which has a tongue extending longitudinally of the ruler and by which the straight edge is se- 110

cured to the ruler, said tongue having a prong struck up from its surface adapted to be embedded in the body of the ruler, said other section adapted to project at a right angle from the ruler and having graduations along one of its edges, said projecting section having a length equal to the width of the ruler and adapted to be folded upon

the fixed section to permit of the ruler being used as originally intended.

The foregoing specification signed at Carson City, Nevada, this 27th day of May, 1916.

DANIEL J. SULLIVAN.
CARLETON F. STEVENS.
